UNITED STATES PATENT OFFICE

ROBERT McC. JOHNSTONE, OF ROSELLE PARK, NEW JERSEY, ASSIGNOR TO CAMERON MACHINE COMPANY, OF BROOKLYN, NEW YORK, A CORPORATION OF NEW YORK

COMBINED SLITTING AND WINDING MACHINE

Application filed August 29, 1924. Serial No. 734,845.

This invention relates to surface winding machines, and is more particularly an improvement on the driving mechanism shown in Patent No. 1,465,967 of August 28, 1923.

In that patent one of the surface winding drums carries an extension which forms the power shaft and from which other elements of the machine are driven. The main object and feature of this invention is to simplify this construction and to render the power unit entirely independent of the winding machine proper to the end that the power unit and the winding machine can be independently assembled and thereafter readily lined up and interconnected.

In the accompanying drawings the invention is disclosed in a concrete and preferred form in which:

Fig. 1 is a general view in side elevation of a winding and slitting machine embodying the invention, with parts broken away and in section for the sake of clearness of illustration.

Fig. 2 is a plan view of one form of an intermediate means for transmitting motion from the power unit to the riding roll.

Fig. 3 is a vertical longitudinal sectional view on the plane of line 3—3 of Fig. 4.

Fig. 4 is a vertical transverse sectional view on the plane of line 4—4 of Fig. 1.

In the embodiment of the invention here disclosed 1 indicates a main frame of any suitable construction in which are mounted two winding drums 2 and 3 spaced apart and rotating in the same direction. These drums act against the wound material 4 on winding shaft 5. 6 is a top pressure or riding roll in a plane above the winding drums and intermediate the same. The winding shaft and riding roll are so mounted in the main frame as to rise as the diameter of the wound material increases in a manner well understood. Suitable slitting means are employed consisting of complementary cutting means of the score cut type. In the present instance a backing roll 7 is mounted in the main frame and associated with this backing roll is one or more score cutters 8.

The material 9, to be acted upon, is led

into the machine, in any suitable way and may pass over guide 10, thence between the slitting elements and thence over one of the drums to the winding shaft.

On the end of each winding drum is a spur gear 11 and on the end of the backing roll is likewise a spur gear 12. These gears project beyond the main frame. Located adjacent the main frame at the side where the gears of the drums and slitting element project is a subsidiary frame 13 which may be bolted to the main frame as at 14. This subsidiary frame carries the power unit. In the present instance this power unit consists of a power shaft 15 mounted in bearings 16 of the subsidiary frame. Motion is imparted to the power shaft by any suitable means but preferably a pulley 17 or other power element and a clutch 18 are used. A brake pulley 19 is also associated with the shaft. The construction and mode of operation of these parts need not be described as they are fully set forth in Patent No. 1,465,967. Power shaft 15 is located in a plane between the two winding drums so that spur gear 20 on said shaft 15 will engage and drive spur gears 11, 11 on the winding drums and will also engage and drive spur gear 12 on backing roll 7.

It will now be understood that the parts of the power unit may be assembled independently of those comprising the winding machines, after which the power unit is lined up with the winding mechanism. This feature is of great advantage in erecting the machine in the field, and also when it is desired to change from a left hand to a right hand machine or vice versa.

It is customary to drive the riding roll by means of a vertical shaft 21, mounted in the main frame, and sliding bevel gears 22. This shaft here extends in a plane between the winding drums intermediate the ends of the drums or main frame and the gears carried by said drums. On the lower end of shaft 21 is a bevel gear 23 which may be driven in any suitable way such as by a bevel gear carried by spur gear 20. In this case it is preferred to mount a stud 24 in the main frame substantially in line with

gear 20 and to mount thereon a bevel gear 25 that meshes with bevel gear 23. Bevel gear 25 is provided with a slot 26 and gear 20 carries a dog 27 engaging said slot. This intermediate mechanism or dog and slot connection is somewhat flexible so that slight inaccuracies in lining up the parts are compensated for. The bevel gear may be mounted on the stud in any suitable way, but preferably a retaining collar 28 and a thrust washer 29 are used so that end thrust in either direction may be taken up.

I claim:

1. A combined slitting and surface winding machine including: two surface winding drums spaced apart and rotating in the same direction, slitting means including a rotating element and score-cut slitters, a gear on the end of each drum, a gear on the rotating element, a power shaft located below and intermediate the gears on the winding drums, a gear on the power shaft meshing with the gears on the winding drums and on the rotating element and transmitting power to all of said gears, a riding roll above the winding drums and intermediate the same, a vertical shaft for driving the riding roll extending downwardly in a plane between the two winding drums and intermediate the ends of the drums and their gears, a bevel gear at the lower end of said vertical shaft, and a bevel gear moving with the gear on the power shaft and engaging the bevel gear on the vertical shaft.
2. A combined slitting and surface winding machine including: a main frame, two surface winding drums spaced apart and rotating in the same direction carried by said main frame, slitting means including a rotating element and score-cut slitters also carried by said main frame, a gear on the end of each drum and projecting beyond said main frame, a gear on the rotating element also projecting beyond said main frame, a subsidiary frame adjacent the main frame at the point where the gears on the drums and rotating element project from the latter, and a power unit, carried by said subsidiary frame, including a power shaft located in a plane below and intermediate the two drums, and a gear on said power shaft meshing with the gears on the winding drums and on the rotating element and transmitting power to all of said gears.

Signed at New York city, in the borough of Brooklyn, county of Kings and State of New York, this 11 day of August, 1924.

ROBERT McC. JOHNSTONE.
